His Attorney.

UNITED STATES PATENT OFFICE

HAROLD H. MAPELSDEN, OF SCHENECTADY, NEW YORK, ASSIGNOR TO GENERAL ELECTRIC COMPANY, A CORPORATION OF NEW YORK

INDICATING CONTROL MEANS FOR INSTRUMENTS

Application filed March 29, 1929. Serial No. 351,092.

The present invention relates to means for positioning, and indicating the position of, the movable control elements of apparatus or instruments, such as radio receivers and the like. More particularly, the invention relates to means of this character which provide a reduction in the rate of movement between a driving and a driven portion thereof, through the medium of a flexible cord wrapped about sheaves on the driving portion and connected with the driven portion to move it positively, the indicating portion being carried by or connected with either portion, but more specifically the driven portion.

Positioning and indicating means of this general character are well known, one common example of a rotary type being that provided in many radio receivers and comprising a rotary driver shaft controlled by a panel knob and connected with a drum on a tuning shaft extending at a right angle thereto by a flexible cord wrapped about the drum substantially mid-way of the length of the cord and wrapped about and secured at its ends to sheaves on the driver shaft.

A flexible cord drive for such means has the advantage that it permits the axes of the driving and driven members to be located at practically and desired angle with respect to each other, because of ability of the cord drive to twist. The cord must, however, be paid out from and be taken up by the driver at substantially the same rate, otherwise backlash or binding occurs. Either of these conditions of operation are extremely undesirable and particularly so in connection with tuning controls for radio receivers and the like. The end or purpose of such control means is of course the convenient and accurate adjustment of the controlled apparatus and to this end the indicating means as well as the positioning means is a contributing factor.

Ordinarily an indicating means for this purpose takes the form of a moving pointer or a moving dial, either illuminated or placed in a position to be readily visible by natural light, and adapted in size and prominence to the size, shape and purpose of the apparatus

with which it is used. In radio apparatus for example, the tuning dial or position indicating means has tended toward reduced size or prominence in the general exterior appearance of the apparatus, necessitating artificial illumination either on or through the dial, for the sake of convenience and ready visibility in operation.

Sufficient illumination of small areas for this purpose often tends to produce the effect of glare. A reduction of this effect to a more comfortable value by a reduction in the visible illumination or by screening has heretofore been accompanied to various degrees by a reduction in visibility.

It is therefore the principal object of this invention to provide an improved indicating control means for instruments which utilizes a cord type of drive and the advantages therein without introducing accompanying disadvantages, and an illuminated indicating means in which the visible illumination is reduced practically to zero while at the same time the visibility of the indication is greatly increased, whereby easy and accurate adjustment of apparatus controlled thereby is permitted to a degree heretofore unknown.

In carrying out the invention, a simple mechanical structure having a single sheave to take up and pay out the cable or drive cord is provided, whereby the latter is unwound from and wound onto the same cylindrical surface and differences in diameter between different sheaves are obviated. Thus accurate positioning means is provided in connection with an indicating means which utilizes a screen on which is projected the image of a moving scale or a portion of the scale within the limits of the size of the screen. The screen is adapted in size to the field of view required and to the size of the apparatus in which the indicating control means is used.

More fully described, the indicating means includes a projector type of dial which is characterized by the fact that the dial moves through a field of light, the area of the dial scale within the field, a minor peripheral portion in the case of a drum type dial, being projected onto the screen, which may

be curved or flat and which carries a fixed indicating means such as a mark in its surface, whereby as the dial moves the image of its scale graduations and indicia moves past the indicating means and in the same surface therewith. The dial scale graduations thus move into and out of view in the same direction as the dial moves and directly across the indicating means.

10 The invention and its further objects and advantages, will be better understood from the following description when considered in connection with the accompanying drawings, and its scope will be pointed out in the appended claims.

In the drawings Fig. 1 is a side view, partly in section of a positioning and indicating means of the rotary drum type embodying the invention; Fig. 2 is a rear view of the 20 same in perspective; Figs. 3 and 4 are side views partly in section corresponding to Fig. 1 and on the same scale, of detail modifications; Fig. 5 is a view in perspective and on the same scale as the preceding figures, 25 of another detail modification; and Fig. 6 is a view of a further detailed modification.

Referring to Figs. 1 and 2, 10 is a portion of a control panel or front wall of an instrument casing in which is located an instrument control shaft 11. In the present example this shaft is journaled in a frame or wall 12 which connects the front panel or wall with a rear wall 13.

The shaft is mounted in other suitable 35 bearings (not shown) and carries a cup or drum 14 provided with a hub 15 by which it is secured to the shaft. The drum and shaft are driven through the medium of a wrapped flexible cord 16 which in turn is 40 connected with a driver shaft 17. The latter terminates in a control knob 18 on the panel front or other suitable location and is suitably journaled in front and rear bearing brackets 19 and 20 respectively which 45 are mounted on the wall 12.

In the present example the apparatus control shaft 11 which may be considered to represent any instrument shaft which it is desired to control, is located within the casing and above the driver shaft 17, and at 50 a right angle thereto. While the invention is not limited to an arrangement of this particular type, it is typical of the usual construction in radio receiving apparatus, which 55 is well known, and is therefore taken by way of example as a suitable construction with which to illustrate the invention.

The cord is wrapped around the drum to 60 provide a secure frictional grip upon it, and is looped through a hole 21 in the drum suitably located to receive it, and through one end of a take-up means comprising a spring 65 22 which is located within the drum cup 14 and which is extensible diametrically of the cup from a fixed pivot stud 23 carried by its

inner wall 24. In the present example the cord ends are tied together at the point of connection with the spring or take-up means, as indicated. The cord is thus positively secured to the drum by the loop through the 70 hole in a manner which does not interfere with the spring connection which represents any suitable resilient means for compensating for changes in the length of the cord.

In case that the shaft 11 is to be extended through the drum, two springs, 75 25 and 26, are provided as shown in Fig. 3. These are secured to suitable pivot studs or to the same pivot stud 23 as shown in the present example, and each spring engages 80 the cord in such a manner that the springs clear the shaft on either side. In the present example these springs engage the cord at two different points 27 and 28. The cord ends are joined preferably at one of said points 85 such as point 28 as indicated. The remaining parts of Fig. 3 are the same as in Figs. 1 and 2 and bear the same reference numerals.

Referring again to Figs. 1 and 2, the cord 90 is wrapped about the drum in a circular path whereby it engages and leaves the drum in two different planes. In the present example it is wrapped about the drum in the form of a helix and one end 29 leaves the helix to pass 95 about an idler pulley 30 which is positioned to cause the cord to pass around a single cylindrical sheave 31 adjacent one end and in substantially a horizontal plane tangent to the sheave. The sheave is carried by and secured to the inner end of driver shaft 17 in a position thus to receive the cord. The cord is then wrapped about the sheave a few turns 100 and is secured to the sheave in any suitable manner, as by passing through a diametrical hole 32 in the sheave and shaft, and then continuing to be wrapped about the sheave. The cord then leaves the sheave and again passes onto the drum in a plane which is substantially vertical and tangent to the sheave, and 105 continues about the drum in its helical path.

With this arrangement the cord is driven 110 by the sheave through the medium of the driver shaft 17 and panel knob 18, and causes the drum to rotate, thereby driving the control shaft 11, and the cord 16 is caused to move in the same helical path about the drum, whereby its tension is not changed perceptibly during the operation of the control shaft by the panel knob 18.

It will be noted in Fig. 1 that while the drive sheave 31 and the drum 14 are relatively close together, the cord is free to move at its ends on long radii represented by the distances between its points of contact with the drive sheave 31 and with the drum and idler pulley 30, and that these radii lie in planes tangent to the sheave and at such angles to each other that the cord is guided in passing about the drum in such a manner 125 130.

- that it has no tendency to shift its position along the drum as the latter is rotated by it. In the present example the cord assumes a helical path on the sheave since the latter at 5 one end is in tangent relation to the cord end which leaves the drum in a rectilinear extension of the helix, and tangent at the other end to the cord end leaving the idler pulley. The idler pulley 30 is mounted upon an arm 10 33 pressed out from bracket 20 and integral therewith, although it may be mounted upon any suitable means which will hold it in a position to carry and guide the cord in the manner above described.
- 15 As an additional means for guiding the cord about the sheave, the latter may be provided with a helical screw thread as indicated at 34, although in certain cases it will be found that this may be dispensed with, since 20 the arrangement of the cord drive is such that the cord will naturally tend to assume a helical form about the drive sheave. Likewise, any other suitable form of connection between the cord and the sheave may be used, 25 such for example as shown in Fig. 4, in which the cord is caused to bind upon itself in a central groove 35 provided in the sheave 31. This latter arrangement has the advantage that the cord may be secured to the sheave by 30 a simple wrapping operation instead of being passed through a hole or other securing means, and permits a considerable saving in time in manufacture and assembly.
- In any case, whether the connection with 35 the sheave be with a groove in which a cord is bound upon itself or any other suitable connection, it will be seen that the cord is wound onto and unwound from the same diameter, since it is connected with a single sheave, and 40 accordingly the cord is paid out and taken up at the same rate without stretching or binding, which action is supplemented and completed by the maintenance of a predetermined path for the cord about the drum and sheave. This arrangement thus provides 45 an accurate and positive drive between the panel knob or other control means and the control shaft 11.
- Associated with the control knob 18 is a 50 panel opening 36 for a position indicating means whereby the relative position of control shaft 11 may be viewed by an operator of the knob 18. In the present example the position indicating means is located in the 55 same plane as and vertically above the driver shaft 17, so that it occupies the same axial space along shaft 11 as the hub 15, the opening 36 being for this reason directly above the control knob 18, although it should be 60 understood that the indicating means may be located in any suitable position in connection with shaft 11.
- In this preferred arrangement, however, a 65 high degree of compactness is obtained with the indicating means located about the hub
- 15 and adjacent to the drum 14. The indicating means comprises a movable member or dial 37, adapted to pass light and having opaque portions defining a scale the graduations of which are projected in an enlarged or magnified form upon a screen 38 by means including a source of light located on the opposite side of the scale from the screen. This source of light may be any suitable means, such as a small electric lamp 39, covered by a 70 shield 40, in which is located an orifice or opening 41. Light from the orifice is projected onto the screen after passing through the scale and provides an enlarged image of a minor portion of the scale upon the screen. 75
- In Fig. 2 the image of the scale graduations is indicated on the screen 38. In this figure it will be seen that a mark or marks 42 are placed in the surface of the screen to cooperate with the image of the scale. These marks may be of any suitable form and in the present example are straight line cuts in the movable member or dial. 80
- The screen is of any suitable transparent or translucent material, and may be either curved or flat for easy visibility. In the present example it is curved on a radius about the axis of shaft 11 and is rendered translucent by sand-blasting upon one or both surfaces, 85 preferably the inner surface. The screen is also preferably of such color that the light image of the scale upon it, which assumes substantially the same color, is pleasing to the eye. Translucent, sand-blasted amber or brown celluloid has been found to give a pleasing color to the image of the scale. 90
- The movable member or dial may assume any suitable form adapted to carry the scale and to move between the source of light and the screen. In connection with a rotary shaft 95 such as shaft 11, it is circular or segmental in form, and mounted in connection with the shaft substantially concentric therewith as indicated in Fig. 1. In the present example, the dial is mounted upon a segmental disk 43 secured to the drum 14. One edge of the dial lies along the peripheral edge of the segmental disk, and the opposite edge rests upon a supplementary supporting segment 44. The 100 latter is joined to the segmental disk 43 by spacing blocks 45 to which the ends of the dial are secured as indicated at 46 (Fig. 2). Along the length of the dial suitable tabs are provided as indicated at 47 (Fig. 1) to hold it in place. 105
- With the indicating means located in the plane of the driver shaft 17 and the plane of hub 15, the drum 14 may be made with any suitable diameter without interfering with the indicating means, and the means providing the source of light for the scale may be placed at any suitable distance from the scale between the latter and the hub 15. In the present example, the shield 40 for lamp 39 is 110 secured to wall 12 by means of screws, one of 115
- 120
- 125
- 130

which is indicated at 48, and the lamp is secured to the shield by a spring clip 49 carried by its socket and adapted to seat upon a bracket 50 projecting from said shield. The lamp is thus removable from the shield for replacement purposes, and when positioned on the bracket is so located that its filament is opposite the orifice opening 41.

The shield is provided about the lamp or between the lamp and the dial in order to prevent a blurring of the image of the scale upon the screen from light reflected through the scale from surfaces about the lamp. In case the reflecting surfaces tend to project light upon or through the dial even when the lamp is provided with a shield as shown, the lamp may be wholly enclosed in a shield of the type shown in Fig. 5, comprising a tubular body 51, one end of which is closed by a flat plate 52 having an orifice opening 53 of any suitable form, such as a rectangle as indicated, and having an opposite end open to receive the lamp 39, and its connected leads 54 which lead to any suitable source of electrical energy (not shown).

The dial or movable scale bearing member may be of any suitable sheet material having transparent or translucent, and opaque or semi-opaque, portions defining graduations and indicia. That is, it may be opaque or semi-opaque in body with translucent, transparent or open graduations and indicia, or it may be translucent or transparent in body with opaque or semi-opaque graduations and indicia. For example, the scale member may be of white or transparent celluloid blackened except for graduations and indicia, or it may be of metal and therefore opaque, perforated to provide open graduations and indicia. The preferred form is the latter, since the perforations permit a greater strength of light to fall upon the screen and the metal is fully opaque so that the contrast between the open graduations and opaque body of the scale members is as much as may be obtained.

The scale member is of such length that it may be graduated to cover the full operating movement of any apparatus with which it is used, and in connection with the usual radio apparatus is slightly over 180° in angular length to cover the 180° movement of the tuning means involved therein. In the drawings, the scale member and driving means is shown at its zero setting and in readiness to be turned in a clockwise direction, as viewed in Fig. 1, the knob 18 being turned for this purpose toward the observer.

The image of the scale as shown in part in Fig. 2, moves into and out of view across the screen and in the same direction as the scale moves. The position of the dial or scale member may be determined by the relation of the image on the screen to the marks 42 provided in or adjacent the screen surface.

As hereinbefore stated the screen 38 may be of other shape than that shown in Figs. 1 and 2 in which the screen is curved. Thus the modification of the invention illustrated in Fig. 6 is the same as that illustrated in Fig. 1 except that in Fig. 6 the screen 38 is flat whereby the dial member 40 is presented in a curved surface in relation to the plane of the screen.

In order that there may be no strain placed upon the cord, drum or shaft 11, a stop for the positioning means is provided in connection with driver shaft 17, whereby an operating force tending to move the dial beyond its limits is met substantially at its source. This stop means may be of any suitable type connected with driver shaft 17 or control knob 18, and in the present example includes a collar 55 freely rotatable upon driver shaft 17 adjacent bracket 19, the collar being provided with an axially extending stud 56 and a radially extending stud 57. The latter stud is adapted to engage an axially extending stud 58 carried by bracket 19, and the former stud 56 being adapted to engage a radially extending stud 59 carried by driver shaft 17. With this arrangement driver shaft 17 is permitted to make substantially two full revolutions between stops, which with the ratio of the diameter of the sheave 31 to the diameter of the drum 14, is just sufficient to carry the scale through its operating range of 180° .

From the foregoing description it will be seen that not only is the control of an apparatus facilitated by the positioning means provided, but the indicating means is also a cooperating factor in the effective control of said apparatus. The illumination of the dial is by this arrangement greatly increased, since the light falls directly on or through the dial, while the visible illumination of the dial is reduced substantially to zero. The scale is not viewed by the eye but only its image on a screen of a color which is pleasing and restful to the eye. There is no glare and there is no error in reading due to parallax, since the image and the mark with which it is compared are in the same observed surface.

It will be seen that by spacing the screen 38 at an increasing distance from the scale, the image of the scale may be proportionately increased in size, whereby the scale is enlarged to any suitable size for any purpose since the scale directly intercepts and receives the image. Likewise, the size of the scale image may be reduced in size by moving the screen closer to the dial, thus permitting one size of scale graduations and indicia to be adapted to a plurality of uses, wherein varying degrees of visibility are required. In connection with radio receivers this is a desirable feature, in that without change of construction the size of the dial indications may be changed to adapt the in-

dications to meet the requirements of the observer. It will also be seen that the control knob and screen are associated or arranged upon the panel whereby the screen may be observed while operating the knob.

It will be observed that in the embodiment shown and described herein, the positioning and indicating means in accordance with the invention, is simple in construction and compact, whereby it may be mounted in apparatus providing a small space for the operating means, such as modern compact radio apparatus for example. Furthermore, the construction is readily adapted for easy manufacture at low cost, since it includes parts which are readily stamped and pressed from sheet metal.

What I claim as new and desire to secure by Letters Patent of the United States, is:

1. The combination of a movable member having opaque portions defining a scale through which light may be passed, a source of light and a shield therefor having an orifice arranged to project light through said scale to provide a projected image thereof, a translucent screen located in spaced relation to said member for directly intercepting and receiving the projected image of the scale, and means including a panel for holding the screen in a fixed position to be viewed.

2. In an indicating control means for instruments, the combination of a movable dial having translucent and opaque portions defining a scale, a source of light and a shield therefor having an orifice for projecting light through said dial to provide a projected image of said scale, and a screen located in spaced relation to said dial and arranged directly to intercept and receive the projected image of said scale.

3. In an indicating control means for instruments, the combination of a movable dial having translucent and opaque portions defining a scale, a source of light and a shield therefor having an orifice for projecting light through said dial to provide a projected image of said scale, a screen located in spaced relation to said dial for directly intercepting and receiving the projected image of said scale, and means for positively moving said dial between said light projecting means and said screen.

4. In a radio receiver, the combination with a movable control element therefor, of a movable scale member, said member being opaque in part and being adapted to permit light to be projected through it in part to provide a scale thereon, a source of light on one side of said member, a shield having an orifice located between said source and said member, and a translucent screen on the opposite side of said member for directly intercepting and receiving the projected image of said scale.

5. An instrument control means including

in combination, a scale member having translucent and opaque portions defining graduations and indicia, a source of light and a shield therefor having an orifice for projecting light through said scale to provide an image of said graduations and indicia, and means for positively moving said scale between said source of light and said screen.

6. A dial device for indicating the adjustment of an instrument to which it is connected having, in combination, means forming a source of concentrated light, a translucent screen, and interposed between said source of light and screen and serving as the sole light-ray modifying means a relatively thin movable member having portions permitting passage of light for forming graduations and light obturating portions forming a background for said graduations, whereby the shadow of said light obturating portions is thrown on said screen, said screen being positioned relatively close to said movable member, and said source of light being positioned at such distance therefrom as will form on said screen a well defined, substantially magnified image of said graduations.

7. A dial device for indicating the adjustment of an instrument to which it is connected having, in combination, means forming a source of concentrated light, a translucent screen, and interposed between said source of light and screen and serving as the sole light-ray modifying means a rotatable, laterally curved, relatively thin member having portions permitting passage of light for forming graduations and light obturating portions forming a background for said graduations, whereby the shadow of said light obturating portions is thrown on said screen, said screen being positioned relatively close to said rotatable member at the convex side thereof, and said source of light being positioned at the concave side thereof at such distance therefrom as will form on said screen a well defined, substantially magnified image of said graduations.

8. A dial mechanism having, in combination, a movable relatively thin member for indicating the degree of movement of the device to which said member is connected, said member having portions permitting passage of light for forming graduations and light obturating portions forming a background for said graduations, a lamp at one side of said member, a translucent screen at the opposite side of said member, said member being presented in a curved surface with relation to the plane of said screen, thereby to effect the projected images of said graduations on said screen so that the graduations visible on said screen will be clearer at a given point than at any other point.

In witness whereof, I have hereto set my hand this 28th day of March, 1929.

HAROLD H. MAPELSDEN. 130
